UNITED STATES PATENT OFFICE.

MILTON H. BERRY, OF EVANSTON, ILLINOIS, ASSIGNOR TO BERRY VENTILATOR COMPANY, OF CHICAGO, ILLINOIS, A CORPORATION OF MAINE.

WINDOW-VENTILATOR.

No. 846,721.

Specification of Letters Patent.

Patented March 12, 1907.

Application filed March 7, 1906. Serial No. 304,611.

To all whom it may concern:

Be it known that I, MILTON H. BERRY, a citizen of the United States, residing at Evanston, in the county of Cook and State of Illinois, have invented certain new and useful Improvements in Window-Ventilators, of which the following is a specification.

My invention relates to that class of ventilators which are designed to prevent a direct current of air or draft upon the occupants of the room upon the opening of the window.

The ventilators of this class with which I am familiar are all of them of considerable bulk, with the result that when they are not in use they occupy a considerable amount of space and are for the most part unsightly and serve to detract rather than add to the furnishings of the house or office.

The object of my invention is to provide a foldable ventilator which will occupy a very small space when closed and which will permit of the opening and closing of the window without causing a direct draft upon the occupants of the room, and has for its further object to provide a ventilator which may be utilized at either top or bottom of the window and which may be so constructed as to be transparent and consequently not obstruct the light when desired, and has for a further object to construct a ventilator which, if desired, may be attached to the window so as to be operated by the opening and closing of the window-sash.

My means of accomplishing the foregoing objects may be more readily understood by having reference to the accompanying drawings, which are hereunto annexed and are a part of this specification, in which—

Figure 1 is an elevation of the inside of a window frame and sash, showing my improved ventilator mounted thereon. Fig. 2 is a vertical transverse section of the same. Fig. 3 is an enlarged detail in section showing parts of my improvement adjacent to the meeting-rails of the sash. Fig. 4 is a detail taken in section above my improved ventilator, showing the same in plane. Fig. 5 is a perspective view of my improved ventilator as it would be when used detached from the sash. Fig. 6 is a vertical section of a modified form of my invention. Fig. 7 is an enlarged detail in section of a part of that construction. Fig. 8 is an enlarged detail, partly

in section, taken at right angles of Fig. 1, 55 showing the method of attaching the vertical movable panel in a modified form of construction.

Similar reference-letters refer to similar parts throughout the entire description. 60

In the drawings, A is a window-casing. This casing may be and preferably is of the ordinary well-known construction with the exception that it is, under some conditions, provided in the inner sides of its side stiles a 65 adjacent to the upper ends thereof with vertical grooves or guideways b of about the proportional length and width shown in Fig. 2.

B is the lower sliding sash of the window, which may be of the ordinary construction 70 or any other construction compatible with the purposes of my invention without involving departure from the scope thereof, and C is the upper sliding sash. This latter is provided at the inner side of its frame with a pane of glass c and at points adjacent to its side bars with upright metallic rods d, which are fixed to and extend between its lower and upper bars and are provided at intervals in their length with indentures or apertures 75 e, Fig. 1, and at their upper ends with threads f, designed for the engagement of vertically-adjustable nuts g', the purpose of which will be presently explained. On the upper side of the top bar or rail of the lower sash B is 80 suitably secured a strip C' of rubber or analogous material, which is designed to lap over the lower bar or rail of the upper sash C when the window is entirely closed, (see Fig. 3,) so as to preclude the passage of air through the 85 joint between the meeting rails or bars of the sashes. Also mounted on the upper bar or rail of the lower sash B are endwise-movable 90

detents D, which are arranged to be seated in the indentures or apertures e of the rods 95 d with a view of fastening the upper sash to the lower sash when the former is lowered for the purpose of ventilation, although it is obvious that both the rods d and their accompanying nuts g', together with the detents D, 100 may be dispensed with without in any way deviating from the spirit of my invention.

E is my novel ventilator as a whole, and F is an adjustable air-excluding device which may be provided above the ventilator.

Where the ventilator is used as shown in Figs. 1 and 2, it may be found desirable in practice to fasten the top of the ventilator

directly to the window-frame, in which event the air-excluding device would not be required.

As shown in the drawings, the ventilator 5 E is open at its ends for the exit of vitiated air and the entry of fresh air, and it is made up of panels g, hinged together at h and bearing panes of glass i, a bottom wall k, preferably of sheet metal, hinged at l to the lower 10 panel g and having apertures m for the passage of air, and a top wall n, hinged at p to the upper panel g and also having apertures m for the passage of air. The bottom wall k and the top wall n, respectively, comprise 15 lapped sections, as shown, which sections are adjustably connected together by bolts r, carried by one and disposed in slots s in the other, whereby it will be seen that the width of the said walls may be readily increased or 20 diminished to amplify or lessen the capacity of the ventilator as conditions demand.

It may be found desirable in practice to construct both the top and bottom wall and the panels of lapped sections in which the 25 slots s may be so arranged as to permit of the manufacture of a ventilator which will be adjustable for windows of various widths.

On its edge remote from the panels g the bottom wall k of the ventilator is provided 30 with lugs t. These lugs are designed to engage the rods d on sash C and be clamped against the upper bar or rail of said sash by the nuts g', and hence it will be apparent that the lower wall k of the ventilator is 35 strongly and yet detachably connected to the sash, it being apparent that any method of fastening may be adopted without deviating from the spirit of my invention.

The top wall n of the ventilator is provided 40 at the ends of its edge remote from the panels g with brackets u, which are disposed and movable vertically in the grooves or guideways b of the frame-stiles a and are provided with a slot and an aperture, respectively, as 45 clearly shown in Fig. 5. The adjustable air-excluding device F is made up of a spring-roller v of the "Hartshorn" or any other suitable type, appropriately mounted at its ends in the brackets u of the ventilator, and 50 a textile or other suitable curtain w, connected at one end to and designed to be wound on the roller v and suitably connected at its opposite end to the crown-bar of the window-casing A, as best shown in Fig. 2.

55 The operation of my device, as shown in Figs. 1 and 2, is as follows: When the detents D are disengaged from the rods d and the sash C is raised to the full extent to close the window, the ventilator E will collapse or 60 fold into a compact bundle, occupying very little space, and the roller v as it approaches the crown-bar of the casing A will take up or wind the curtain w, and consequently it will be apparent that when idle or not in use the

ventilator will take up but a minimum 65 amount of space at the top of the window. When, however, the upper sash C is lowered to the extent shown, the ventilator E will be drawn downwardly and opened, while the curtain w will be caused to close the space intermediate the ventilator and the crown-bar of the casing A. In its open position the ventilator E, because of the transparency of its panels g, will not appreciably interfere with the passage of light through the window and 70 yet will obviously prevent a direct draft of air from striking persons located adjacent to the window. It will be noticed, however, that in virtue of the open ends and the foraminated bottom and top of the ventilator 75 air is enabled to freely pass into and out of the compartment, and consequently the maintenance of a pure atmosphere in the apartment is assured, which is an important desideratum. During the upward movement of the sash C the ventilator-panels g, 80 will by reason of their being hinged together and to the bottom and top walls, swing outward, while when the sash is moved downward said panels g will swing inward to the 85 position shown in Figs. 2 and 5.

In the modified construction shown in Figs. 6 to 8 the ventilator E', which is generally similar to the ventilator E, is carried by the lower sash B', and an adjustable air-excluding device F' is provided between said ventilator and the sill x of the window-casing A'. An air-excluding device F' is shown in these views, but practice has shown that it is often desirable to secure the bottom of the ventilator directly to the lower part of the windowsill x, in which event obviously the air-excluding device would not be needed. When used, it is preferable in the form of a panel having a pane of glass or other transparent material i' to prevent its excluding the light, and it is disposed in a pocket y, formed in the sill x, and is provided with projections z, Fig. 8, designed to bring up against complementary abutments z' on the pocket-walls, whereby it will be seen that it is held against withdrawal from the pocket. 100

In the practical use of the modified construction the ventilator E' and the device F' assume positions shown when the sash B' is 105 raised and for the purpose before described with reference to the ventilator E and the device F, while when the sash is lowered the ventilator E' collapses or folds into a compact bundle and the device F' is sheathed in 110 the pocket y.

When desired, the construction shown in Figs. 6 to 8 may be reversed—that is to say, the pocket y may be formed in the crown-bar of the casing A' and the panel F' arranged in 115 said pocket and above the ventilator carried by the upper sash. In this latter case I contemplate providing turn-buttons (not shown) 125

on the side stiles of the casing for supporting the panel F' when the ventilator is disconnected from said panel.

I prefer to detachably connect the ventilator E' and the panel F', and this through the medium of one or more spring-pressed plungers a², as shown in Fig. 7.

It will be gathered from the foregoing that my improvements are located at the inner side of the window, where they are protected from the weather, and that they are at once simple and durable in construction and neat in appearance.

I have specifically described the construction and relative arrangement of the parts embraced in the present embodiments of my invention in order to impart a definite understanding of said embodiments. I do not desire, however, to be understood as confining myself to such specific construction and relative arrangement of parts, as changes or modifications may be made in practice which will fairly fall within the scope of my invention as claimed.

25 It may be found desirable in practice to utilize a ventilator as shown in Fig. 5, in which case the lower wall k may be secured to the window-sill x and a handle provided for the top wall n. Where this is done, it will 30 not of course be attached to the window at all, and it will be possible to open the window without raising the ventilator.

Having described my invention, what I claim, and desire to secure by Letters Patent, is—

1. The combination with a window, of a ventilator arranged to open and close synchronously with the opening and closing of the window; the said ventilator being open 40 at its ends and having a transparent wall barring the direct passage of air and also having foraminated bottom and top walls.

2. The combination with a window, of a ventilator arranged to open and close synchronously with the opening and closing of the window; the said ventilator being open 45 at its ends and having a transparent wall barring the direct passage of air and also having sectional foraminated walls which 50 are adjustable as to width for the purpose set forth.

3. The combination of a window-casing, a sliding sash therein, a ventilator arranged to open and close with the sash, and an adjustable or movable air-excluding device interposed between and connecting the ventilator 55 and the casing.

4. The combination of a window-casing, a sliding sash therein, a collapsible or foldable 60 ventilator arranged to open and close with the sash; the said ventilator being open at its ends and having a transparent inner wall, and an adjustable or movable air-excluding

device interposed between and connecting the ventilator and the casing. 65

5. The combination of a window-casing, a sliding sash therein, a collapsible or foldable ventilator arranged to open and close with the sash; the said ventilator being open at its ends and having an inner wall formed by 70 transparent panels hinged together, and bottom and top, foraminated walls hinged to the inner wall, and an adjustable or movable air-excluding device interposed between and connecting the ventilator and the casing. 75

6. The combination of a window-casing, a 80 slidable sash therein, a ventilator arranged to open and close with the sash, a spring-roller carried by the ventilator, and a curtain connected to and adapted to be wound on the roller and also connected to the casing.

7. The combination of a window-casing, a lower slidable sash, an upper slidable sash carrying rods, means on the lower sash for engaging said rods, a ventilator connected 85 with the rods and arranged to open and close with the upper sash, a spring-roller carried by the ventilator, and a curtain connected to and adapted to be wound on the spring-roller and also connected to the casing. 90

8. The combination of a window-casing, a sliding sash therein, and a ventilator disposed at the inner side of the sash and connected with the same and also with the casing; the said ventilator being open at its 95 outer side and at one or both of its ends.

9. The combination of a window-casing, a sliding sash therein, and a ventilator disposed at the inner side of the sash and connected with the same and also with the casing; the said ventilator being open at its 100 outer side and at one or both of its ends and having a transparent inner wall.

10. The combination of a window-casing, a sliding sash therein, a ventilator disposed at the inner side of the sash and connected with the same and also with the casing; air-excluding means arranged at the juncture of the sashes and movable therewith, and means for locking said excluding means at 105 intervals to the casing.

11. The combination with a window; of a collapsible ventilator connected with the window and arranged to be unfolded and opened on the opening of the window. 115

12. The combination with a window; of a collapsible ventilator connected with the window and arranged to be unfolded and opened on the opening of the window and having a transparent wall for barring the direct passage of air. 120

13. In a device of the character described, the combination with a window of a ventilator, said ventilator being provided with a top and bottom, a side wall hinged to the top 125 and bottom, said wall being formed with a

plurality of folds to permit the ventilator to be expanded to register with any point to which the window may be opened.

14. In a device of the character described, the combination with a window of a ventilator, said ventilator being provided with a top and bottom and side wall, said wall being formed with a plurality of folds to permit the ventilator to be expanded to register with any point to which the window may be opened.

15. In a device of the character described, the combination with a window of a ventilator, said ventilator being provided with a top and bottom, a side wall of lapped sections hinged to the top and bottom, said wall being formed with a plurality of folds.

16. In a device of the character described, the combination with a window of a ventilator, said ventilator being provided with a top and bottom and a side wall of lapped sections, said wall being formed with a plurality of folds.

17. In a device of the character described, the combination with a window of a ventilator formed with a plurality of sections, their adjacent edges being pivotally connected and adapted to fold in a compact form.

18. The combination with a window of a foldable device to deflect the air-currents entering when the window is open, said device

being constructed of sections hinged to each other and adapted to expand to register with the opening of the window.

19. The combination with a window of a foldable device to deflect the air-currents entering when the window is open, said device being constructed of telescoping and hinged sections adapted to expand to register with the opening of the window.

20. In a device of the character described, the combination with a window of a ventilator having each end open, said ventilator being provided with a top, the said top being perforated, a side wall formed with a number of folds to permit the ventilator to be expanded to register with the opening of the window.

21. In a device of the character described, the combination with a window of a ventilator having each end open, said ventilator being provided with a top and bottom, the said top being perforated, a side wall formed with a number of folds to permit the ventilator to be expanded to register with the opening of the window.

In testimony whereof I affix my signature in presence of two witnesses.

MILTON H. BERRY.
